[57] CLAIM

The ornamental design for an ignition switch lock, as shown.

DESCRIPTION

FIG. 1 is a top plan view of an ignition switch lock showing our new design;

FIG. 2 is an end elevation view thereof;

FIG. 3 is a side elevation view thereof, the opposite side being a mirror image of the side shown;

FIG. 4 is an end elevation view thereof opposite to that shown in FIG. 2;

FIG. 5 is a bottom plan view thereof;

FIG. 6 is a perspective view thereof; and

FIG. 7 is a perspective view thereof in open condition.

*Fig. 1.**Fig. 2.**Fig. 3.**Fig. 4.**Fig. 5.*

*Fig. 6.**Fig. 7.*
